DESIGN FOR A DISPLAY STAND FOR TOILET BRUSHES OR SIMILAR ARTICLE

Eric Leopold Hugo Cosby, Jr., London, England

Application February 9, 1948, Serial No. 144,377
In Great Britain November 25, 1947

Term of patent 14 years

(Cl. D80—9)

To all whom it may concern:

Be it known that I, Eric Leopold Hugo Cosby, Junior, a subject of the King of Great Britain, residing at London, England, have invented a new, original, and ornamental Design for a Display Stand for Toilet Brushes or Similar Article, of which the following is a specification, reference being had to the accompanying drawings, forming a part thereof.

Figure 1 is a front perspective view of a display stand for toilet brushes or similar article showing my new design with the top portion being broken away for convenience of illustration; and

I claim:

The ornamental design for a display stand for toilet brushes or similar article, as shown.

ERIC LEOPOLD HUGO COSBY, JR.
